BLADE-DISPENSING MAGAZINE

Meyer J. Shnitzler, Brookline, and Michael D. Benedict, Jr., Lynn, Mass.

Application May 19, 1949, Serial No. 2,759

Term of patent 14 years

(Cl. D58—12.6)

To all whom it may concern:

Be it known that we, Meyer J. Schnitzer and Michael D. Benedict, Jr., both citizens of the United States, residing at 17 Greenough Circle, Brookline, Massachusetts, and 77 Ashland Street, Lynn, Massachusetts, respectively, have invented a new, original, and ornamental Design for Blade-Dispensing Magazines, of which the following is a specification, reference being had to the accompanying drawings, forming part thereof.

In the drawings:

Fig. 1 is a view in perspective of a blade-dispensing magazine showing our new design; and

Fig. 2 is a similar view showing the dispensing magazine in inverted position.

We claim, the ornamental design for a blade-dispensing magazine, as shown.

MEYER J. SHNITZLER.
MICHAEL D. BENEDICT, JR.
